UNITED STATES PATENT OFFICE.

FEDELE ANGELILLO, OF NEW YORK, N. Y.

LOCK.

Application filed May 3, 1926. Serial No. 106,199.

This invention relates to locking devices as applied to doors and windows whereby the same may be secured within their casings at the top and bottom as well as the front.

5 It is one of the objects of this invention to provide a simple and efficient lock of the class described so arranged that all of the several bolts employed are actuated simultaneously by rotating a single hand knob.

10 It is a further feature to provide means for positively retaining the bolts in an extended, operative position until key released.

Other features and advantages will appear in the following detailed description, taken 15 into connection with the associated drawings, and in which:—

Figure 1, is a front elevational view of a lock made in accordance with the invention, the cover plate being removed and the bolts 20 shown in extended position.

Figure 2, is a similar view of the same but showing one of the longitudinal bolts retracted and held from operation, the other in released condition ready for retraction, 25 and the transverse bolt withdrawn.

Figure 3, is a transverse sectional view taken on line 3—3 of Fig. 1.

The lock casing, generally designated by the numeral 10, is of conventional type, and 30 oblong rectangle in shape, provided with a straight face wall 11, its sides and ends containing a recess 12, to receive a cover plate, not shown, which may be held in place by bolts passed through the openings 14.

35 Rotatably mounted in the casing are the reduced ends 15 of roll-back 16 having a square axial opening 17 to receive the usual square spindles of ordinary door knobs.

40 A radially extending lug 18 on the roll-back is operably engageable in a notch 19 formed in the adjacent side edge of a transverse latch bolt 20 having the usual bevelled end 21 extending through the casing, the same being held in a normally projected position by a coiled expansion spring 22 disposed within a recess 23 in the bolt and guided in the usual manner.

45 A stud 24 extends from the lock face 11 through the recess 23 to receive the thrust of the spring, and at the outer end of the bolt 20 is a stop 25 limiting its forward movement.

50 The lock bolt latch 20 contains another recess or slot 26 into which enters a guide 27 formed on the face plate 11, the construction

of the foregoing parts being of common type.

A lock tumbler cylinder roll-back 28 similar to the knob roll-back 16 is provided with lugs 30 and 31, spaced to appropriately enter a notch 32 in the adjacent side edge of a 60 transverse lock bolt 33, arranged parallel and spaced from the latch bolt 20.

The lock bolt 33 has a thickened forward portion 34 extensible through the casing; a stop 35 is formed on the opposite, inner end 65 of the bolt and on its inner side is a detent 36 the purpose of which will later appear.

In the portion of the bolt opposite the notch 32 is an open recess 37 into which extends a post 38 fixed on the plate 11, and 70 pivoted to the bolt by a pin 39 is a tumbler or latch plate 40 having two spaced notches, respectively 41 and 42 either of which are engageable with the post 38 and when so engaged retain the bolt in locked or un- 75 locked position.

A flat spring 43, fastened to the bolt 33 normally presses the latch plate into operative engagement with the post 38 at one or the other positions of the plate and the 80 plate is provided with an arm 44 having a curved end to be engaged by either of the lugs 30 or 31, as the roll-back 28 is turned, and simultaneously with shifting the bolt, the latch plate being raised by the arm to clear the post at each operation in either direction of bolt movement.

85 A longitudinal bolt 45 passes outwardly of the upper end wall of the casing, its inner reduced end 46 being guided by fixed 90 studs 47 which also serve to receive the thrust of compression spring 48 encircling the reduced portion of the bolt, the outward movement of which is limited by a washer 49 fixed to the end of the bolt to abut the 95 studs opposite the spring.

At a point adjacent the shoulder of the bolt, against which the spring 48 impinges, are two spaced notches 50 and 51 respectively, in either of which is receivable a 100 detent 52 carried on the transverse dead bolt 33, whereby the longitudinal bolt 45 may be held in its adjusted position.

105 Shifting or adjustment of the bolt 45 is thus provided for: a lug 53 on the knob roll-back 16, at a right angle to the lug 18, is engageable with a shoulder 54 in a recess 55 in the adjacent edge of the bolt 45 when the latter is in a raised or operative position, and if the bolt 33 be retracted to withdraw 110

the detent 52, the bolt 45 will be drawn out of the engagement with its keeper by properly actuating the door knob.

When the bolt 45 is retracted the recess 55 permits the lug 53 to rotate freely without affecting the bolt; and if it be desired the bolt may be maintained in its retracted position by a slide 56 having a detent 57 engageable in an opening 58 in the bolt, the slide being movable by a knob 59 having a stem passing through the casing wall to connect with the slide.

In a similar manner an oppositely disposed longitudinal bolt 60 passes through the opposite wall of the casing, its stem 61 being guided by posts 62 and is actuated by a spring 63, limited by a fixed collar 64.

The bolt 60 contains a recess 65 having a shouldered portion 66 to be operatively engaged by a lug 67 on the knob roll-back 16 directly opposite the lug 53; another recess 68 in the same edge but at a point below, clears the lugs 30 and 31 when the key roll-back is operated.

In the outer side of the bolt 60 are two spaced notches 69 and 70, each being respectively receptive of the detent 36 carried on the transverse dead bolt 33, whereby the bolt 60 is positively maintained in either of its adjusted positions.

A recess 71 in the bolt 60 is receptive of a detent 72 carried by a slide 73, actuated by a knob 74 in the manner previously described.

In operation, the parts being in locked or operative position, as shown in Fig. 1, and it be desired to unlock the same, the key roll-back 28 is rotated to bring the lug 30 or 31 into engagement, first with the arm 44, raising the spring actuated latch 40, releasing the bolt 33 and permitting it to be shifted inwardly by continued rotation of the key roll-back the bolt 33 becoming locked by the end of its movement and the longitudinal bolts released from the detents 52 and 36.

Thereafter by rotating the door knob the roll-back lugs 53 and 67 move the longitudinal bolts 45 and 60 inwardly to clear their ends from their keepers as will be readily understood.

Obviously a reversal of operative movements will cause locking arrangement of the several bolts in an effective manner.

The bolts 45 and 60 may be permanently restrained by their respective slides 53 and 73, and when so restrained will not interfere with the operation of the dead bolt 33 which may be projected when the longitudinal bolts are either projected or retracted.

It will be understood that minor changes may be made in the structure of the parts, including their arrangement, without departing from the general scope and tenor of the appended claims, and also that portions of the invention may be used without others.

Having thus described my invention and set forth the manner of its construction and application, what I claim as new and desire to secure by Letters Patent, is:—

1. In a lock of the class described the combination with a casing, a knob actuated roll-back and a key actuated roll-back, of a pair of longitudinal bolts mounted in opposed relation in said casing, a transverse dead bolt therein adapted to project beyond the casing and having means for locking the longitudinal bolts in projected position, said key roll-back adapted to retract the dead bolt and release the longitudinal bolts, and means operated by the knob roll-back to retract said longitudinal bolts.

2. A lock comprising a casing, a pair of longitudinal bolts mounted in opposed relation in said casing, a transverse dead bolt therein adapted for projection beyond the casing, means carried by the dead bolt for locking the longitudinal bolts in projected position and means to retract the dead bolt said means also serving to release the longitudinal bolts.

3. In a lock of the class described the combination with a casing, a knob actuated roll-back and a key actuated roll-back, of a plurality of latch bolts, and an intersecting dead bolt slideable in said casing and adapted to be projected therefrom, said key actuated roll-back adapted to project and retract the dead bolt and said knob actuated roll-back adapted to retract said latch bolts simultaneously.

4. In a lock of the class described the combination with a casing, a knob actuated roll-back and a key actuated roll-back, of a pair of longitudinal latch bolts, a dead bolt adapted to project beyond the casing and a transverse latch bolt slidably mounted in said casing, said key actuated roll-back adapted to project and to retract said dead bolt to lock or release the longitudinal bolts, and knob actuated means to simultaneously retract the latch bolt and said longitudinal bolts.

5. In a lock of a class described the combination with a casing, a knob actuated roll-back and a key actuated roll-back, of a plurality of longitudinal bolts, a dead bolt projectable from the casing and having means to lock the longitudinal bolts and a transverse latch bolt slidably mounted in said casing, said key actuated roll-back adapted to retract said dead bolt and release the longitudinal bolts, and said knob actuated roll-back adapted to simultaneously retract the latch bolt and said longitudinal bolts, and independent means to retain said longitudinal bolts when in retracted position.

6. A lock comprising a casing, a pair of longitudinal latch bolts slidably mounted in opposed relation in said casing, a transverse dead bolt projectable from the casing, a

latch bolt parallel with said dead bolt, key actuated means to operate said dead bolt, the movement thereof locking or releasing said longitudinal bolts, and knob operated means to actuate said longitudinal bolts and said latch bolt simultaneously.

7. A lock comprising a casing, a pair of longitudinal bolts slidably mounted in opposed relation in said casing, a transverse dead bolt projectable from the casing, a latch bolt parallel with said dead bolt, detents carried by said dead bolt, to engage said longitudinal bolts, means for actuating said dead bolt to secure and to release the longitudinal bolts, and means to shift the latch bolt and said longitudinal bolts in unison.

8. A lock comprising a casing, a pair of longitudinal bolts slidably mounted in opposed relation in said casing, a transverse dead bolt projectable from the casing, a latch bolt parallel with said dead bolt, detents carried by said dead bolt to engage said longitudinal bolts, means for actuating said bolt to secure and to release the longitudinal bolts and to shift the dead bolt to projected or retracted position, means to shift the latch

bolt and said longitudinal bolts in unison, and means to restrain one or both of said longitudinal bolts when retracted. 30

9. The combination in a lock having a casing and a plurality of latch bolts therein, of means for operating all the latch bolts simultaneously, and means for rendering inoperative all but one of the latch bolts while permitting the operation of a single latch bolt independently of the others. 35

10. The combination with a lock having a plurality of latch bolts and means for operating all of them simultaneously, of means 40 to restrain all but one latch bolt in retracted position without interfering with the free operation of the remaining unrestrained latchbolt, a dead bolt projectable from the casing having means for projecting and retracting same, means carried by the dead bolt to lock all of the latch bolts in projected position and means to permit the dead bolt to be projected when the latch bolts are in either projected or retracted position. 45

Signed at New York, in the county of New York and State of New York, this 27th day of March, 1926.

FEDELE ANGELILLO.
